Must O'Keefe(57) **ABSTRACT**

A lancing device with an ejector that is movably retained with a housing in proximity to a lancet and is selectively movable between a home position, a first eject position, an intermediate position defined by contact of the ejector with the lancet, and a second eject position. The ejector is rotatable to move from the home to first eject position and is linearly translatable to move between the first and second eject positions. The ejector includes an arm that extends within the housing and engages the lancet, an exterior portion that is actuated by a user, and a post extending therebetween. The post extends through a slot in the housing which limits the linear movement and direction of the ejector. Upon rotation of the ejector, the arm extends through an opening at the rear of the carriage holding the lancet to permit access to the lancet.

LANCING DEVICE WITH EJECTOR**CROSS-REFERENCE TO RELATED APPLICATIONS**

The present application is a continuation-in-part of co-pending U.S. patent application Ser. No. 16/577,862, filed on Sep. 20, 2019, which claims the benefit of U.S. Provisional Application Ser. No. 62/734,433, filed on Sep. 21, 2018, the contents of all of which are incorporated herein by reference in their entireties.

STATEMENT REGARDING FEDERALLY SPONSORED RESEARCH OR DEVELOPMENT

This invention was made with government support under HD088139 awarded by the National Institutes of Health. The government has certain rights in the invention.

FIELD OF THE INVENTION

The present invention pertains generally to the field of medical devices, and more specifically to an ejector for a device for making an incision, such as by lancing.

BACKGROUND

Blood collection is routinely necessary in the medical profession to assess, diagnose and monitor patient conditions and health. For example, blood samples are obtained from nearly every neonate born in the U.S. for numerous preventative screenings and diagnostic tests. The heel stick method, by which a sharp penetrates a superficial capillary bed of the foot to cause a small bleed, is the most common collection method. The procedure is considered moderate to severely painful, ranking in the top 25% by clinicians for common painful neonatal intensive care unit (NICU) procedures. It is conducted frequently, such as daily, during a NICU stay which can be weeks long. Studies also suggest that pain and stress responses caused by heel sticks are due to both the heel lance itself and by the post-lance heel squeezing for blood collection. Painful heel sticks may increase patient anxiety and fear of subsequent procedures, a side-effect of which is vasoconstriction which may impair blood collection. The immature pain system in preterm neonates has been characterized by hypersensitivity, overlapping receptive fields, prolonged windup periods, and immature descending inhibition. Additionally, there is a correlation between pain from heel sticks and free-radical generation, potentially risking exposure to oxidative stress. Together, these factors predispose neonates to a greater level of clinical and behavioral sequelae compared to older age groups.

These painful heel stick procedures occur during a critical developmental window previously associated with epochal brain development. Evidence suggests that exposure to repetitive painful experiences and analgesic drugs may cause excessive NMDA/excitatory amino acid activation, resulting in excitotoxic damage to developing neurons in neonates. This may alter pain sensitivity (e.g., hyperalgesia), and impact behavioral changes (e.g., increased anxiety, stress disorders, attention deficit disorder), and even potentially lead to impaired social skills and self-destructive behavior. Reducing neonatal pain and distress would therefore lead to long-term clinical improvements, such as by limiting neuronal excitotoxicity/apoptosis.

Clinical practice has evolved to address the need to reduce pain and improve heel stick efficacy. Today, it is essentially universally accepted that spring-loaded/automatic lancets are superior to manual techniques in terms of consistent performance, efficacy, pain, and safety. Clinicians have also explored numerous strategies to further reduce heel stick pain including pharmacological and non-pharmacological means, including oral sucrose, glucose, non-nutritive sucking, kangaroo care/skin-to skin contact, electrical stimulation, white noise, breastfeeding, music, and massage. Prolonged exposure to analgesic drugs has been implicated in permanent altering of the neuronal and synaptic organization of the neonatal brain and is thus less desirable. Non-pharmacological methods have shown varying levels of promise, with sucrose and non-nutritive sucking appearing to be some of the most effective and widely adopted strategies. Sucrose or pacifier usage is not always safe, such as for low gestational age (GA) infants, as it may lead to increases in short-term adverse effects, such as choking, oxygen desaturation, and bradycardia. Administration of sucrose may not be indicated for infants with unstable or high blood sugars. Furthermore, repeated doses of sucrose may put infants at risk for poorer neurodevelopment. Many other pain relief strategies are limited in terms of efficacy, practicality, available equipment, and disruption to normal practice. A solution is needed that provides drug-free reduction of the pain and stress responses from heel sticks and post-lance heel squeezing in neonates.

In NICUs and infant-mother nurseries, the current heel stick approach involves inserting a sharp lancet or blade into a neonate's heel, targeting a superficially capillary bed, followed by squeezing the heel causing blood to surface. Many current devices, such as those identified below, use a swinging motion that creates an incision through the capillary bed. Current newborn heel stick recommendations, based on postmortem and ultrasound studies, advise to perform the lance incision on the most medial or lateral portions of the plantar surface of the heel, not on the posterior curvature of the heel; to penetrate no deeper than 2.2 mm; and to avoid repeated incision through previous puncture sites that may be infected. These recommendations are in place to avoid calcaneal puncture and osteochondritis risk. Moreover, the capillary-rich beds in newborns are located at the dermal-subcutaneous junction between 0.35-1.6 mm below the skin surface, while pain fibers increase in abundance >2.4 mm below the skin surface.

Common heel lancing devices currently in use include the Tenderfoot®, Gentleheel®, QuikHeel™, Sterilance®Baby, TinyTouch™, and NeatNick® lancets which use a single thrust activation to advance the sharp into the heel then retract, but do not provide anesthesia. The blades produce an incision that ranges in depth from 0.85-1.0 mm and width 1.75-2.50 mm, depending on product. The incision shape is relatively shallow to cause less pain but must be wide to transect many capillaries to collect sufficient blood volumes. Vibration has also been used in some applications to attempt to mask the pain response.

The concept draws on Melzack and Wall's Gate Theory of Pain, in which tactile stimulation masks the neural pain signals at the level of the spinal cord to produce a vibrational anesthesia effect. Vibrational anesthesia has proven effective for reducing pain associated with injections, such as local anesthetic injections, various dermatology procedures, eyelid surgery, venipuncture, intramuscular injections, and botulinum toxin injections.

Certain devices employ vibrational anesthesia in off-label use, such as the DentalVibe®, the Buzzy®, and various

vibrational massage devices. For instance, the DentalVibe® is a dental tool having a pair of arms that are positioned on either side of an injection site. Once in contact with the patient's gums, the arms are vibrated, applying light vibration to the tissues around the injection site. Anesthesia injections are administered by a separate device while the tissue on either side of the injection is vibrated. Therefore, the DentalVibe® requires two-handed operation or two practitioners participating in the procedure—one to operate the DentalVibe® and one to perform the injection. It is also an injection, such as for Novocaine®, rather than lancing for blood collection.

Buzzy® is a device used in conjunction with injections, which combines cold and vibration to block out pain. Wings are frozen prior to use, then are attached to the device. Buzzy® is placed on the patient's skin, at the target injection site, with the frozen wings in direct contact with the skin. Buzzy® vibration is activated and held on the injection target site for 30-60 seconds, before being moved proximally in the direction of the head or spine for injection administration. Contact with the skin, and therefore application of cold and vibration, is maintained at the proximal site during injection administration to the pre-cooled/vibrated target injection site. Following injection administration, Buzzy® can be returned to the injection site to aid in post-delivery pain relief. However, while useful for injections delivering material, cold would be contraindicated for heel sticks, since cold is known to decrease blood flow which would inhibit blood collection from a heel lancing procedure.

Other devices externally add vibration to needles or syringes during injection delivery. For instance, the Vibra-Ject™ is a syringe attachment encompassing a vibrating motor that imparts non-directional vibration to the syringe. Similarly, Vibrovein™, is a micro-mechanical motor which attaches to commercial syringes and delivers a transverse vibration to the needle. However, neither of these devices have the means to deliver vibration-induced anesthesia prior to needle insertion, rather focusing on delivering vibration to the needle itself during needle insertion.

Therefore, a need exists in the medical industry for heel stick lancing devices that can reduce pain and trauma, in a non-pharmacological manner, while simultaneously providing sufficient blood flow for collection, preferably without having to squeeze the infant's foot further. Such a device could also be used for other lancing and quick stick procedures, not limited to infant heel sticks.

Additionally, removal of lancets from heel stick and lancing devices once they have been used can be dangerous for the user of the device. Typically, removal of such lancets requires grasping the lancet at the opening of the device and pulling to release, requiring the user to interact with the sharp end of a used instrument to remove. This runs a risk of puncture to the user during the removal process. It also requires two hands to perform—one to hold the device and another to grasp and pull on the lancet. This two-handed nature combined with the risk of puncture slows down the clinical use of the device to ensure safety.

Some lancet devices have ejectors included within the housing that push the lancet out of the housing when activated. However, many of these still require the user to put their hands near the lancet's piercing tip for removal. For instance, the ONE TOUCH® DELICA® by Johnson & Johnson Corp. includes a distal cap that retains the lancet within the housing during use. However, this distal cap must be manually removed before the ejector can be activated, otherwise the lancet will not be expelled from the housing.

Moreover, the distal cap is secured to the housing during use to make sure the lancet does not inadvertently come loose during use. Because of this strong connection, the distal cap must be twisted to unsecure from the housing and remove it. 5 Therefore, removal of the distal cap still requires two hands and engaging the distal end of the device near the piercing end of the lancet. Similar mechanisms of action are also employed in other devices, such as ONE TOUCH® DELICA® PLUS by Johnson & Johnson Corp. and the 10 CARE TOUCH® lancing device with ejector by Future Diagnostics LLC.

It would therefore be beneficial to have a lancing device with an ejector that did not require placing the user's hands near the piercing or lancing tip to remove the lancet from the 15 device. It would also be preferable if this ejector could remove the lancet without the need for use of both hands.

SUMMARY

20 The present invention is directed to a lancing device that combines vibration-induced anesthesia with a high-speed automatic lancet in a single handheld device that provides vibration-induced anesthesia to the lancing site prior to and during lancing procedure. Despite the vibration, it provides 25 depth control for the lancing procedure, yielding high reliability and reproducibility of expected collection volumes. Therefore, the present device causes less pain and trauma responses without compromising blood sample quality or collection volume.

30 The device includes a housing, a lancet having a piercing member, and a contact surface disposed to contact the skin of the patient prior to and during lancing. The contact surface stimulates the skin at the target site to be lanced continually both before and during lancing procedure, masking 35 neural pain signals at the level of the spinal cord, producing a vibration-induced anesthesia effect. Due to the pain inhibition potential of the device of the present invention, the piercing member of the lancet can penetrate slightly deeper, to about 1.8-2.0 mm target depth, and with a 40 narrower incision, of about 1 mm, while yielding comparable blood volume to known automatic lancets. Because smaller cuts are produced, repeat sampling is possible when necessary.

45 A wide range of commercially available single use lancets may be inserted and retained in the housing of the present device during use, which can be removed or ejected following use. The housing may include a carriage that receives and retains the lancet in the device and maintains the alignment of the lancet with the opening of the housing 50 through which the piercing member extends when deployed for incision. The carriage may be suspended within the housing or otherwise isolated from the housing walls by an isolation assembly. The distal end of the lancet includes a contact surface that is configured to contact the patient's 55 skin when the lancet is in use. In some embodiments, the first end of the housing may include a contact surface configured to contact the patient's skin, rather than the lancet, when the device is in use.

60 A motor in mechanical communication with the tactile member(s) produces vibration when activated. Accordingly, the vibrations may be transferred through the lancet or a portion of the housing. These vibrations are transferred to the skin in contact with the tactile member(s) when the motor is activated. The concept draws on Melzack and 65 Wall's Gate Theory of Pain, in which tactile stimulation masks the neural pain signals at the level of the spinal cord to produce a vibrational anesthesia effect. The motor is

capable of delivering vibration with up to 0.5 mm displacement when the device is in contact with skin, producing a 50% reduction of lancet insertion force for the piercing member and consistent incisions for high reliability in collection.

An isolation assembly is disposed within the housing and is configured to dampen the vibrations between the motor and the portion of the housing held by a user or operator when in use. For instance, in some embodiments the isolation assembly may include springs such as those used to hold the carriage in suspension. In other embodiments it may be an elastomeric material disposed in a portion of the housing that absorbs vibration and restricts the vibration from the remainder of the housing. Regardless of location or type, the isolation assembly isolates the users' hand from the vibrations affecting the tactile member(s), providing greater comfort to the device operator. The handheld housing may also have an ergonomic shape for comfort.

The present invention therefore offers many improvements over known lancets. It minimizes pain and anxiety for patient and their loved ones. It improves outcomes by reducing distress associated with lancing procedures such as heel sticks. It is handheld and therefore easy to use. It can accommodate any lancet, which is preferably disposable for increased ease of use and hygiene. It can be used for any lancing or quick stick procedures for blood collection, such as but not limited to neonatal heel sticks, glucose testing, metabolic testing, allergy testing and others, and is particularly useful when repeated sticks to the same area are necessary.

The present invention is also directed to an anesthetic lancing device with an ejector for removing the lancet. The ejector includes an exterior portion that is accessible from the outside of the device, preferably the top, and an interior portion that interacts with the lancet for removal. The exterior portion includes an actuator that can be engaged by the user, such as to rotate and push the exterior portion of the ejector. A post extends from the exterior portion through a slot in the housing and into the interior space of the device. An arm extends radially outwardly from the post, such as at the terminal end thereof. The post is rigidly fixed to the exterior portion so that when the exterior portion of the ejector moves, the post and attached arm also move in the same manner and direction.

The ejector is movably retained within the housing and is selectively positionable between a home position, a first eject position, and a second eject position. An intermediate position also exists between either the home and first eject position or between the first and second eject positions. Indicia on the top of the housing and an indicator on the exterior portion of the ejector coordinate to easily and quickly tell the user what position the ejector is in at any given time. In the home position, the ejector is as distanced from the lancet as possible, with the arm of the ejector spaced apart from the lancet. In at least one embodiment, the arm is parallel to and spaced apart from the rear of the lancet in the home position. When the actuator is rotated, such as up to 90°, the ejector rotates similarly into a first eject position. In this position, the arm is also rotated so it is aligned with the rear of the lancet. In at least one embodiment, the arm is partially within the carriage holding the lancet and is angled perpendicular to and pointing toward the rear of the lancet in the first eject position. In some embodiments, the arm may be still spaced apart from the rear of the lancet in this first eject position. In other embodiments, the arm may come into contact with the rear

of the lancet, defining an intermediate position, during rotation to the first eject position.

As the actuator is pushed distally toward the first end of the device, the exterior portion slides distally along a track 5 in the top of the housing and the post slides distally along the length of the slot. Similarly, the arm moves distally within the housing, further into the carriage. In some embodiments, the arm moves closer to the lancet until it contacts the rear of the lancet in an intermediate position during this distal 10 translation along the slot. In other embodiments, the arm is already in contact with the lancet before translational motion along the slot begins. Regardless of where contact with the lancet begins, further force on the actuator causes the arm to push on the lancet, overcoming the frictional forces holding the lancet in the carriage and pushing the lancet out of the housing. The ejector may be moved until the post reaches the end of the slot, halting further forward movement and defining the second eject position, which is the distal-most 15 position for the ejector. The lancet is ejected from the device at or by this point. A biasing member biasing the post relative to the housing returns the ejector back to the first eject position within the housing once pressure on the actuator is released. The exterior portion is then rotated to 20 move the ejector back into the home position.

Thus, the ejector of the lancing device of the present invention is in the home position when the device is in use, during which the lancet will not inadvertently be expelled from the device. Because the actuator of the ejector is 25 located on the top of the housing, it is not in the way of operating the lancet for piercing or activating and deactivating the motor for vibration during piercing. However, once it is desired to remove the lancet, the ejector can be 30 easily operated to rotate the ejector and move it forward to push the lancet from the device. Notably, this operation can occur with the same hand that is holding the device, allowing for one-handed operation, and can be performed by a single thumb or finger. It also does not require the user to put their hand near the distal end of the device and the piercing 35 member of the lancet, making it safer for the user as well.

The anesthetic lancing device, together with its particular features and advantages, will become more apparent from the following detailed description and with reference to the appended drawings.

DESCRIPTION OF THE DRAWINGS

FIG. 1A is a top perspective view of one embodiment of the anesthetic lancing device of the present invention.

FIG. 1B is a top perspective view of a second embodiment of the anesthetic lancing device of the present invention.

FIG. 1C is a top perspective view of a third embodiment of the anesthetic lancing device of the present invention.

FIG. 2A is a partially exploded view of the housing of the anesthetic lancing device of FIG. 1A.

FIG. 2B is a fully exploded view of the interior components of the anesthetic lancing device of FIG. 2A.

FIG. 3 is bottom perspective view of the inside of the housing top and underside of carriage, showing the restriction members.

FIG. 4 is a top plan view of the interior of one embodiment of the anesthetic lancing device.

FIG. 5 is a cut-away side view of the interior of the anesthetic lancing device taken along line 5-5 from FIG. 1A.

FIG. 6 is a front perspective exploded view of one embodiment of the lancet and carriage of the anesthetic lancing device.

FIG. 7 is a back perspective exploded view of the carriage and pressure spring of the anesthetic lancing device of FIG. 6.

FIG. 8 is a bottom perspective view of one embodiment of the carriage and motor of the anesthetic lancing device.

FIG. 9 is a bottom plan view of the of one embodiment of the interior of the anesthetic lancing device.

FIG. 10A is a top plan view of one embodiment of the of the interior of the anesthetic lancing device with the carriage in a first compressed position, ready for the application of vibration.

FIG. 10B is a top plan view of the exterior of the anesthetic lancing device of FIG. 10A.

FIG. 11A is a top plan view of the one embodiment of interior of the anesthetic lancing device with the carriage in a second compressed position, ready for triggering the lancet.

FIG. 11B is a top plan view of the exterior of the anesthetic lancing device of FIG. 11A.

FIG. 12A are graphical data of mean SC activity during glucose screening (left) and metabolic/other screening (right) from Example 1.

FIG. 12B are graphical data of NFCS scores for glucose screening (left) and metabolic/other screening (right) in neonatal patients from Example 1, comparing the present anesthetic lancing device to control.

FIG. 13A are graphical preliminary data of average electroencephalogram (EEG) signals from the pilot study in Example 2 synchronized to lance across subjects by treatment, comparing the present anesthetic lancing device to control.

FIG. 24C is a partial cutaway view of the lancing device with ejector of FIG. 24A, showing the interior components from the bottom in a first eject position.

FIG. 25A is a top plan view of the lancing device with ejector of FIG. 22A, shown in a second eject position.

FIG. 25B is a partial cutaway view of the lancing device with ejector of FIG. 25A, showing the interior components from the top in a second eject position.

FIG. 25C is a partial cutaway view of the lancing device with ejector of FIG. 25A, showing the interior components from the bottom in a second eject position.

Like reference numerals refer to like parts throughout the several views of the drawings.

DETAILED DESCRIPTION

The present invention is directed to a vibration-inducing anesthetic lancing device 100 and its method of use. This device 100 is handheld and used to create an incision for subsequent blood draws, utilizing vibration for a drug-free reduction of pain and stress response from patients, for improved success rates and sample volumes. It thus provides many benefits to the collection of blood, particularly from 60 neonates or other patients who may be subjected to multiple or repeated blood draws. The anesthetic lancing device 100 is preferably sized and dimensioned for single-handed use

and may preferably have an ergonomic shape to facilitate ease of handling and operation.

As can be seen from FIGS. 1A-2B, the anesthetic lancing device 100 having a first end 106 and opposite second end 108. The device 100 is configured so the first end 106 may receive a lancet 140 and is positioned in proximity to the skin of a patient when the device 100 is in use. The second end 108 will therefore be closer to the user or operator of the device 100. The device 100 includes a housing 110, 110' which retains the other components of the device 100. The exterior of the housing 110, 110' provides an outer surface that can be comfortably held and operated by a user. The housing 110, 110' may be made of any suitable material, such as but not limited to biocompatible or medical grade plastic, ABS plastic, stainless steel, and other polymeric, plastic or metallic material or combinations thereof. The housing 110, 110' may be manufactured by any suitable method, including but not limited to deposition, subtractive rapid prototyping (SRP) milling, 3D printing, molding or other techniques. The housing 110, 110' is also sized and dimensioned to be held and operated by a single hand of the user. Further, in at least one embodiment the housing 110, 110' may be comprised of a top 111, 111' and bottom 112, 112' that correspondingly secure together to form a housing, and which may be selectively separated for access to the interior of the housing 110, 110' and its components when needed, such as for maintenance, repair or replacement of a part.

In some embodiments, the housing 110 may also include at least one restriction member 113 extending into the interior space of the housing 110, as shown in FIG. 3. The restriction member(s) 113 may extend from the top 111 or bottom 112 of the housing 110, though preferably from the underside of the top 111 in at least one embodiment as shown in FIG. 3. The restriction member(s) 113 are positioned and have a length sufficient to limit or restrict the rotational movement of the lancet 140 within the housing 110. Thus, the restriction member(s) 113 keep the lancet 140 from twisting or rotating out of alignment when the cap of the lancet 140 is removed from the head 144, which typically occurs by twisting or rotating the cap to break its connection to the head 144. To accomplish this, the restriction member(s) 113 are configured to contact at least a portion of the lancet body 142 and/or carriage 150 into which the lancet 140 is inserted when a twisting motion would otherwise rotate the lancet 140, preventing further rotational movement in the direction of the torque being applied.

With reference to FIGS. 1A-5, the anesthetic lancing device 100 also includes a lancet 140 removably retained within the housing 110, 110'. Specifically, the lancet 140 may be a single-use lancet 140 that is inserted through an opening 115 in the housing 110, 110' and retained in the anesthetic lancing device 100 for use and then is removable from the device 100 after use for replacement by a fresh lancet 140. The lancet 140 may be any commercially available or proprietary lancet, such as but not limited to the safety lancet Unistik®3—Neonatal (Owen Mumford Ltd., Oxfordshire, England) indicated for neonatal heel sticks. For instance, the lancet 140 may include a body 142 with a head 144 at one end and a piercing member 146 disposed therein. The body 142 may include a spring (not shown) that biases against and moves the piercing member 146 in the head 144 upon being deployed, as described in greater detail below. The head 144 therefore also includes an opening with which the piercing member 146 is aligned and through which the piercing member 146 passes when deployed and retracted.

The head 144 may be at least partially covered by a cap (not shown) when not in use, to protect the piercing member 146 from accidental sticks and maintain the sterility of the head 144. The cap may be removed from the head 144 such as by a twisting action once the lancet 140 is positioned within the anesthetic lancing device 100.

The device 100 further includes a contact surface 148 disposed at the first end 106 of the device 100 and configured to contact the skin of a patient when the device 100 is placed against the skin for use. The contact surface 148 is disposed on the lancet head 144 and/or housing 110 in proximity to and at least partially surrounding the opening 115 through which the piercing member 146 extends when deployed. Accordingly, the contact surface 148 is positionable at the target lancing site for piercing. As used herein, the terms “incision” and “lancing” may be used interchangeably. The contact surface 148 is configured to contact the patient skin and provide a vibrations to the lancing site that are perceived by the patient’s brain, masking the sensation of the piercing member 146 when deployed and reducing the pain experienced by the patient.

In some embodiments, the contact surface 148 may be the distal end 145 of the lancet head 144, as shown in FIG. 1B. In other embodiments, the contact surface 148 may be located on the first end 106 of the housing 110, such as shown in FIG. 1C, such as when the lancet 140 is recessed within or flush with the housing 110 rather than extending therefrom. In some embodiments, such as when the lancet 140 is flush with the housing 110, the contact surface 148 may include both the distal end 145 of the lancet head 144 and the first end 106 of the housing, as in FIG. 1C. In certain embodiments, the contact surface 148 may include at least one tactile member 148', such as in FIGS. 1A, 2A, 4 and 5, which may extend from the head 144 of the lancet 140. One non-limiting example of such tactile member(s) 148 may be found in the UniStick®3—Neonatal lancet (Owen Mumford Ltd., Oxfordshire, England). In other embodiments, such as shown in FIG. 1B, the tactile member(s) 148' may extend from the housing 110' at the first end 106, such as the top 111' and/or bottom 112' of the housing 110' rather than the lancet head 144'. When present, the tactile member(s) 148 may be of any shape, size and configuration, such as but not limited to beads, nubs, geometric shapes or patterns, linear or curvilinear and combinations thereof. For instance, in at least one embodiment the tactile member(s) 148 protrude about 0.5 mm from the surface of the head 144 and/or housing 110'. In some embodiments, the tactile member(s) 148 may provide friction between the device 100 and the skin of the patient to facilitate or enhance vibration.

As shown in FIG. 5, the piercing member 146 is affixed at the head 144 of the lancet 140. The piercing member 146 may be any sharps member suitable for lancing, such as but not limited to a needle, blade, or scalpel tip, and may be solid or hollow. For instance, in at least one embodiment, the piercing member 146 may be a solid needle having a gauge in the range of 18G to 30G and a diameter in the range of about 0.85 to 2 mm, though other gauges and diameters are also contemplated herein. In at least one preferred embodiment, the piercing member 146 may be a solid 18G needle with a 1 mm diameter. The gauge or diameter of the piercing member 146 determines the width of the incision. The piercing member 146 of the present device 100 therefore provides a narrower incision than other current heel stick methods, which create an incision shape that is relatively shallow for less pain but must be wide to transect sufficient capillaries for sufficient collection volume. The piercing member 146 is also configured to penetrate to a depth of no

11

more than about 2-2.5 mm, preferably to a depth of about 1.8 mm. The piercing member 146 therefore goes deeper into the capillary-dense dermal-subcutaneous junction below the skin than other current lancet procedures for heel sticks, while still avoiding the increased density of dermal pain fibers that occur beyond 2.4 mm below the skin surface. Accordingly, the piercing member 146 in the present device 100 provides a narrower but deeper incision than current heel stick methods.

The piercing member 146 is preferably held within the head 144 in a retracted state when not deployed, such as prior to and following lancing. In the retracted state, the piercing member 146 does not extend beyond the surface of the head 144, as shown in FIG. 5. Therefore, the lancet 140 may be considered a "safety lancet" in which the piercing member 146 can only contact and pierce the skin when deployed, thus preventing accidental sticks for safety and hygiene reasons.

The lancet 140 also includes a lancet trigger 149 on the body 142. In at least one embodiment, the lancet trigger 149 may be a lever, button, or other structure on the exterior of the lancet 140 and which may be actuated to release the spring-loaded piercing member 146 and deploy the piercing member 146 through the opening 115 of the head 144 to make an incision or otherwise pierce the skin. The lancet 140 is preferably configured to automatically retract the piercing member 146 after deployment and store the piercing member 146 within the body 142, preferably preventing the piercing member 146 from leaving the body 142 again.

With reference to FIG. 2A, the anesthetic lancing device 100 includes a trigger 116 that extends from the exterior surface of the housing 110. In at least one embodiment, the trigger 116 extends through the top 111 of the housing 110 and is aligned with the lancet trigger 149 of the lancet 140. A spring or other biasing member (not shown) may be included within the trigger 116 such that the trigger 116 is maintained in an up position. When a user presses down on the trigger 116 from the exterior of the device 100, the trigger 116 is depressed and contacts the lancet trigger 149, also depressing the lancet trigger 149 and causing the piercing member 146 to be deployed. Accordingly, the trigger 116 may be used to activate the lancet 140 within the device 100. The trigger 116 may be made of any material that will withstand the force necessary to depress it, such as but not limited to ABS plastic and stainless steel and may be made of medical grade or biocompatible materials.

The housing 110, 110' is configured to receive and retain the lancet 140 inserted therein for use. In at least one embodiment, such as shown in FIGS. 2A-7, the anesthetic lancing device 100 may also include a carriage 150 within the interior of the housing 110 that is specifically configured to receive and retain the lancet 140 within the device 100. The carriage 150, when present, may be used to properly seat and align the lancet 140 for use. To that end, the carriage 150 is located near the first end 106 of the device 100 in order to receive the lancet 140. The carriage 150 may be made of any suitable material, such as but not limited to ABS plastic, stainless steel, aluminum, or other material suitable for use in medical devices. The carriage 150 may be made of the same or different material as the housing 110, 110' or the lancet 140.

The carriage 150 may include a bottom 153 on which a portion of the lancet 140, such as the body 142, rests when inserted. The carriage 150 also includes at least one guide member 155 that is positioned to guide the lancet 140 into the housing 110 in proper alignment. In at least one embodiment, as shown in FIGS. 2A-7, the carriage 150 includes a

12

pair of guide members 155 disposed on either side of the bottom 153 and which act as barriers to restrict lateral movement of the lancet body 142, thereby centering the lancet 140 in the housing 110, 110'. The guide members 155 may extend from the bottom 153 of the carriage 150 and may extend to the underside of the top 111 of the housing 110, 110' in at least one embodiment. The carriage 150 also includes a back plate 156 which is positioned to receive the rearward terminal end of the lancet body 142 that is opposite the head 144. The back plate 156 is therefore disposed at the end of the carriage 150 furthest from the first end 106 of the housing 110, 110' and opening 115 through which the lancet 140 is inserted. The carriage 150 may also include at least one, but preferably a plurality of retention members 154 configured to removably retain the lancet 140 within the carriage 150 once inserted. The retention members 154 may cooperatively work to retain the lancet 140 within the carriage 150. For instance, the retention members 154 may have a frictional fit against a portion of the lancet 140. In at least one embodiment, the retention members 154 may be made of a resilient material such as but not limited to ABS or any other polymers with sufficient yield strength so they may be temporarily flexed, deflected or deformed to accommodate the passing of the lancet 140. They may also be spring-biased or otherwise biased against the lancet 140 such that the lancet 140 pushes against the retention members 154 during insertion into the housing 110, 110' and the retention members 154 may push back against the lancet 140 when it is positioned within the carriage 150. When the lancet 140 is selectively removed from the housing 110, 110' after use, the retention members 154 may return to their resting conformation. The retention members 154 may be disposed anywhere along the carriage 150 to facilitate the maintenance of the lancet 140 in position, such as but not limited to on either side of the carriage 150, and therefore lancet 140, such as shown in FIGS. 2A, 6 and 7.

The carriage 150 is mounted within the interior of the housing 110, 110'. In some embodiments, the carriage 150 may be directly affixed to the inner surface of either the top 111 or bottom 112 of the housing 110, 110'. In a preferred embodiment, however, the carriage 150 is movably mounted to the housing 110, 110' through an isolation assembly 160. The isolation assembly 160 is configured to connect the carriage 150 to the housing 110, 110' in a way that permits the vibration or movement of the carriage 150 but insulates this movement or vibration from being transmitted to the housing 110, 110', and thus to the hand of the user.

In at least one embodiment, as shown in FIGS. 2A-7, the isolation assembly 160 may include at least one, but preferably a plurality of isolation members 162 disposed between and connecting the carriage 150 to the housing 110, 110'. As shown in this embodiment, the isolation members 162 may be springs having a sufficient length and spring constant to suspend the carriage 150 within the interior space of the anesthetic lancing device 100 so the carriage 150 does not contact the housing 110, 110' but is also sufficiently flexible to absorb the vibrations and movements of the carriage 150. For example, the spring isolation members 162 may have a length in the range of 5 to 20 mm and preferably about 10 mm and may have a spring constant in the range of 25 to 100 N/m and preferably about 50 N/m. There may be any number of isolation members 162 between the carriage 150 and the housing 110, 110', such as but not limited to two, three, four, six or eight. In the embodiment shown in FIGS. 2A-7, there are four such isolation members 162, one near each corner of the carriage 150. In other embodiments, the isolation member 162 may

be a barrier made of vibration absorbing material at least partially surrounding the carriage 150 and/or lancet 140. For instance, materials such as but not limited to potting material, low durometer silicone such as NuSil™ MED 2-4013 fast cure silicone adhesive (NuSil Technology LLC, Carpinteria, California), or any polymeric material with some elasticity for absorbing vibration may be used as the isolation member 162 when acting as a barrier.

The carriage 150 may also include at least one connection point 164 where the corresponding isolation member 162 contacts and/or connects to the carriage 150. The connection point(s) 164 may be co-extensive with the surface of the carriage 150 or may be recessed in or extending from the surface of the carriage 150. In the embodiment shown in FIGS. 6-8, the connection points 164 are nubs, knobs, or other extensions that protrude from the surface of the carriage 150, such as the side surface of the carriage 150. They may have any shape, size or configuration. As shown in FIGS. 6-8, the connection points 164 may be sized to receive the corresponding isolation member 162, such that the connection point 164 fits within the inner diameter of the isolation member 162. Thus, the connection point 164 may help hold up the carriage 150. The isolation member 162 may be affixed or secured to the connection point 164 at one end and the housing 110, 110' at the other end and may be releasably secured or permanently secured. In at least one embodiment, the isolation member 162 is permanently secured to the connection point 164, such as by adhesive, bonding, welding or other similar method of secure attachment.

The device 100 may also include at least one alignment member 158 configured to maintain the carriage 150 in alignment within the housing 110, 110'. For instance, as shown in FIGS. 4, 5 and 7, an alignment member 158 may extend from a portion of the housing 110 into the interior space where the carriage 150 is located. The back of the carriage 150 may include an aperture 157 through which the alignment member 158 is received. The aperture 157 is therefore at least as large as the alignment member 158 and may be large enough that the carriage 150 can move relative to the alignment member 158 in one direction, such as along the length of the alignment member 158 but is restricted from much movement in other directions. For instance, in the embodiments of FIGS. 2A-7 and as best depicted in FIG. 5, the carriage 150 may be movable along the length of the alignment member 158 in an axial direction that is in line with or parallel to the axial direction of the lancet 140 and the piercing member 146 thereof. However, the alignment member 158 limits movement of the carriage 150 along a vertical axis, such as upward in the direction toward the top 111 of the housing 110 or downward in the direction toward the bottom 112 of the housing 110. This may be particularly useful in embodiments in which the carriage 150 is suspended within the interior space of the housing 110 by an isolation assembly 160 since the isolation members 162 would permit movement in any direction, including along the vertical axis as described above, depending on the elasticity or spring constant of the isolation members 162. For instance, when the user presses down on the trigger 116, it contacts and presses down on the lancet trigger 149, as described above. This pressure also forces the entire lancet 140 down, along with the carriage 150 in which it resides, since the carriage 150 is elastically suspended. The isolation members 162 would flex or stretch in response to such downward pressure, allowing the entire carriage 150 and lancet 140 to be moved downwardly toward the housing 110, rather than triggering the lancet trigger 149. However, the

alignment member 158 extending through the aperture 157 of the carriage 150 limits movement of the carriage 150 in the downward direction as limited by the size of the aperture 157. This prevents the carriage 150 from being pushed into the bottom 112 of the housing 110 and ensures that the lancet trigger 149 will be activated. It also maintains the suspended positioning of the carriage 150 and the alignment of the lancet head 144 relative to the opening in the housing 110 so the piercing member 146 may extend through the housing 110 upon the lancet 140 being triggered.

The anesthetic lancing device 100 also includes a force indicating system which senses the amount of force applied to the lancet 140 from contact with the patient's skin and may indicate to the user when sufficient force has been achieved to begin vibration and/or triggering the lancet 140 for piercing. This may be helpful since a certain amount of skin contact is necessary to achieve the pain masking ability of the vibration of the anesthetic lancing device 100. If too little contact or force is achieved, the patient will not sufficiently feel the vibration at the target incision or lancing site and the pain sensation may be not sufficiently masked. If too much force is applied, the vibrations from the device 100 may be damped which would decrease the anesthetic effect. Therefore, the force indicating system allows a user to achieve the optimal results for pain masking. It also provides a method of using the anesthetic lancing device 100 to achieve more uniform results, both from the same user over different lancing procedures and between different users. Current lancet operation requires the user to apply their own judgment on how to hold and press the lancet against the skin for operation, which leads to variability in results. The present anesthetic lancing device 100 avoids this variability and provides more uniformity, allowing busy medical staff and even non-medically trained individuals to perform lancing procedures efficiently and consistently.

The force indicating system may be a mechanical or electrical system that registers or detects force applied to the lancet 140 from pressing the device 100 on the target site and reports this information to the user for operating the device 100. The force indicating system includes at least one force sensor 172 configured to detect, measure and/or respond to force applied to the lancet 140. For instance, in at least one embodiment such as shown in FIGS. 2A-5 and 7, the force sensor 172 may be a spring or other elastomeric structure biased against the lancet 140 within the housing 110, preferably axially in line with the lancet 140. Specifically, the force sensor 172 spring may contact and be biased against a portion of the carriage 150, such as the back plate 156 of the carriage 150. A connection point 164' along the back plate 156 of the carriage 150, as shown in FIG. 7, may be configured to receive and/or contact the force sensor 172 spring such that the force sensor 172 spring is preferably in line axially with the lancet 140 when positioned within the carriage 150. The opposite end of the force sensor 172 spring may be secured to a portion of the housing 110, such as the bottom 112. In other embodiments, the force sensor 172 may be an electronic pressure detector positioned anywhere in contact with the lancet 140, housing 110 and/or carriage 150.

When the operator or user contacts the lancet 140 with the skin of the patient at the target lancing site and applies pressure, the lancet 140 will be pushed further into the housing 110 toward the second end 108 along the longitudinal axis of the lancet 140. The carriage 150 will also move with lancet 140 since the lancet 140 is secured therein and the carriage 150 is movable relative to the housing 110. The force sensor 172 detects the amount of pressure or force applied by the lancet 140, such as by the force sensor 172

spring compressing between the lancet 140 and/or carriage 150 and the housing 110. As the lancet 140 and/or carriage 150 moves rearwardly in the direction of the second end 108 of the housing 110, the force sensor 172 spring increases in compression and the carriage 150 moves axially along the alignment member 158, which ensures the carriage 150 does not deviate too far laterally to either side and the piercing member 146 remains aligned with the opening 145 in the housing 110.

The pressure indicating system 170 also includes at least one, but preferably a plurality of indicators 174 presented to or perceivable by the user that provide information on the force applied to the lancet 140 based on information from the force sensor 172. The indicators 174 therefore assist the user in operating the anesthetic lancing device 100. These indicators 174 may be mechanical or electrical in nature. For instance, in at least one embodiment as shown in FIG. 7, the indicators 174 may be indicia on a portion of the carriage 150 that indicates certain force currently being applied to the lancet 140. The indicia may be any suitable indicia, such as but not limited to markings, colorings, icons, geometric patterns, letters, numbers and other mechanical markings. In other embodiments, the indicators 174 may be electrical such as but not limited to lights, such as LEDs, which may be colored or white light and may be present in different colors or change in intensity, blink or flash to provide information on pressure as detected by the force sensor 172. Regardless of type, the indicator(s) 174 may be viewable or otherwise perceivable to the user during operation. For instance, in at least one embodiment, the indicator(s) 174 may be viewable to a user through a window in the housing 110, 110', such as in the top 111, 111' of the housing 110, 110' as shown in FIGS. 1A-2B, 10B and 11B. In other embodiments, the indicator(s) 174 may be present on the sides of the housing 110, 110', such as when they are lights. In still other embodiments, the indicator(s) 174 may be vibrations, such as pulses, emitted by the device when certain predefined pressure thresholds are reached and which may be detected by the user through tactile sensations in the hand that grasps the device 100. In still further embodiments, the indicator(s) 174 may be a sound emitted by a speaker associated with the force sensor 172 configured to produce a sound when certain predefined pressure thresholds are reached. Such sounds may be beeps, alarms, chimes, or other audibly detectable noises. The indicator(s) 174 may include any combination of the above.

In at least one embodiment, as shown in FIGS. 2A-5, 7 and 10A-11B, the indicators 174 may be mechanical markings on a portion of the carriage 150. There may be different indicators 174 each representing a different specific pressure range or value. For instance, a first indicator 174a may be positioned along the carriage 150 to indicate a first pressure and a second indicator 174b may be positioned to indicate a second pressure which is greater than the first pressure. In the embodiment of FIGS. 2A-5, 7 and 10A-11B, the first and second indicators 174a, 174b may be located at terminal ends of the guide members 155 of the carriage 150 which are disposed in proximity to the underside of the top 111 of the housing 110 such that they are configured to align with and be visible through corresponding first and second indicator windows 120a, 120b, respectively, of the top 111 of the housing 110 when certain corresponding pressures are sensed by the force sensor 172. Accordingly, the first and second indicators 174a, 174b may be located along different portions of the carriage 150 such that different ones of the indicators 174a, 174b are presented and viewable through the indicator windows 120a, 120b when the corresponding

pressure is sensed. In certain embodiments, there may be a single indicator window through which the various indicators 174a, 174b are viewable when the corresponding pressure is sensed. Thus, the indicators 174a, 174b may be positioned at different locations of the same portion of the carriage 150, such as along the same guide member 155. In other embodiments, such as shown in FIGS. 2A-5, 7 and 10A-11B, the indicators 174a, 174b may be located on different guide members 155 and are viewable through dedicated indicator windows 120a, 120b, respectively, of the housing top 111.

In at least one embodiment such as shown in FIGS. 2A-5, 7 and 10A-11B, the first indicator 174a is indicative of a first force range or value that is predetermined to be optimal for beginning vibration of the anesthetic lancing device 100. In use, when a user operating the device 100 first contacts the patient at the target lancing site with the device 100, such as with the head 144 of the lancet 140 secured therein, there is minimal force detected by the force sensor 172. As the user pushes the device 100 against the patient, the force increases, pushing the lancet 140 and therefore carriage 150 increasingly rearwardly and compressing the force sensor 172 spring. At a certain point, sufficient force will have been applied to bring the first indicator 174a into alignment with the first indicator window 120a such that the user may then see the first indicator 174a through the first indicator window 120a. This positioning tells the user that sufficient force has been detected that vibration of the device 100 can be initiated, as described below. This corresponds to a pressure that allows the vibration to be detected by the patient to mask the pain response. For instance, in at least one embodiment the first indicator 174a corresponds to a force in the range of about 0.001 to 10 N and preferably about 1 N. This may be referred to as a first position of the lancet 140 and/or carriage 150, such as shown in FIGS. 10A-10B.

The user may continue pressing the device 100 further against the target site once vibration has commenced. This applies increasing force to the lancet 140, carriage 150 and force sensor 172 and further moves the lancet 140 and carriage 150 in a rearward direction toward the second end 108 of the housing 110. At a certain point, the second indicator 174b becomes aligned with and may be viewable through the second indicator window 120b in the housing top 111. When the second indicator 174b is viewable, a second force has been detected by the force sensor 172. This second force is therefore a higher or greater amount of force than the first force indicated by the first indicator 174a. The second indicator 174b is indicative of a force at which the device 100 may be triggered to release or deploy the piercing member 146 for lancing or incising the skin of the patient at the target lancing site, and which will provide a sufficiently deep incision to achieve sufficient volume of blood collection but is also a low enough pressure that the incision will avoid the piercing member 146 reaching the nerve-dense portion of the dura. For instance, the second force may be in a range of about 2 to 10 N and preferably about 3 N. This may be referred to as a second position of the lancet 140 and/or carriage 150, such as shown in FIGS. 11A-11B.

Any number of indicators 174 may be provided, each representing a different pressure or pressure range at which actions can be taken, such as but not limited to starting vibration, stopping vibration, actuating the trigger 116 to deploy the piercing member 146 and others. The force sensor 172 and indicator 174 placement may therefore be selected and/or calibrated to the desired pressures or pressure ranges for respective activities desired. In certain embodiments, such as in electrical pressure indicating sys-

tems 170, the device 100 may be configured such that only certain actions may be taken when certain pressures are indicated by the force sensor 172 and/or indicators 174. For instance, an electrical circuit may remain open until the second pressure is achieved and the second indicator 174b is activated, at which point the circuit may be closed. This would prevent the trigger 116 from being actuated and the piercing member 146 from being deployed before sufficient pressure is achieved, thus ensuring a sufficient amount of time has elapsed for vibration to produce an anesthetizing effect and/or that proper depth will be reached. Similarly, the circuit may be again opened once too much pressure is achieved, thereby preventing the triggering of the piercing member 146 when it would be deployed too deep within the skin of the patient, thereby avoiding the nerve-dense area of the skin. In mechanical embodiments, a blocking member may restrict contact between the trigger 116 and lancet trigger 149 until the second pressure is sensed or detected by the force sensor 172, achieving the same result. In other embodiments, however, the indicators 174 may be useful to a user but not required for operation of the device 100, such that a user or operator may have the freedom to use the device 100 at whatever pressure they see fit.

The anesthetic lancing device 100 also includes a motor 180 that is configured to produce vibrations when activated which are then transferred to the contact surface 148. The motor 180 may be any suitable motor for a handheld device, such as but not limited to a disc motor, DC motor, off-balance DC motor, piezoelectric motor or other type motor. For instance, in at least one embodiment the motor 180 may be a disc motor rated for up to 12,000 rpm at 3 V_{DC}, preferably operative at about 10,000 rpm, and may have a diameter up to 10 mm but more preferably up to about 1 mm and still more preferably about 0.4 mm. In at least one other embodiment, the motor 180 may be a DC motor operative to produce vibrations sufficient to vibrate the contact surface 148 at a frequency in the range of 50-500 Hz, preferably in the range of about 140-200 Hz, and still more preferably about 150 Hz.

The motor 180 is affixed to the housing 110 or carriage 150 in mechanical communication with the lancet 140. For example, in at least one embodiment as shown in FIGS. 5 and 8, the motor 180 may be secured underneath the carriage 150 near the first end 106 of the device 100, such as to the underside of the bottom 153 of the carriage 150 on the opposite side of the same surface on which the lancet 140 rests in the device 100. Accordingly, vibrations produced by the motor 180 are transmitted through the bottom 153 of the carriage 150 and to the lancet 140, thereby vibrating the contact surface 148 on the head 144 of the lancet 140 accordingly. In other embodiments, the motor 180 may be mounted within the housing 110 at the first or second end 106, 108 of the device 100 to a portion of the housing 110 such that vibrations are transmitted to the contact surface 148 regardless of whether it is located on the head 144 of the lancet 140 or on the first end 106 of the housing 110. In such embodiments, an isolation member 162 such as a barrier may be disposed at least partially around the portion of the housing 110 where the motor 180 is mounted, to dampen the vibrations felt by the user or operator while not dampening the vibrations transmitted to the lancet 140 or first end 106 of the housing 110. Regardless of where the motor 180 is mounted, it may be secured to the housing 110 or carriage 150 by any suitable method, such as but not limited to adhesive, bonding, screws, and other secure fasteners.

The motor 180 is configured to produce vibrations when turned on or activated. Preferably, this vibration may be

multi-directional vibration that is not specific to any axis or direction, though in certain embodiments the vibrations may be directed along a particular axis, such as in line with, co-extensive or parallel to the longitudinal axis of the lancet 140 and therefore the piercing member 146. A scotch-yoke mechanism, swashplate or other similar mechanism may be used to convert rotational motion of the motor 180 to an axial motion for a specific directional vibration or oscillation. As used herein, the terms "vibrate" and "oscillate" may be used interchangeably.

The motor 180 is configured to produce vibrations that, when transmitted, will cause the contact surface 148 to vibrate or oscillate at a displacement in the range of up to 1 mm, preferably about 0.5 mm. As noted previously, this vibration or oscillation may be omni-directional, laterally (side-to-side), longitudinal (axially) or a combination thereof. The contact surface 148 vibrates against the skin of the patient at the target lancing site to provide pain masking sensations. In some embodiments, the vibrations may also be transferred to the piercing member 146 such that the piercing member 146 also vibrates while penetrating the skin at the target lancing site.

The motor 180 may be powered by a power source 130, such as shown in FIGS. 5 and 9. The power source 130 is in electrical communication with the motor 180, such as through wires 182, 184, 186 shown in FIG. 9, though other configurations are also contemplated herein. In at least one embodiment, the power source 130 is retained within the housing 110, such as a battery or batteries. Such battery may be a AAA or AA battery, a coin cell battery, 3V battery, or other similar batteries capable of providing sufficient power to operate the motor 180 and may be rechargeable or single use. In other embodiments, the power source 130 may be located externally from the housing 110 and may be connected in electrical communication with the motor 180 through wires or cables which run to and from the housing 110.

The motor 180 may be activated and deactivated through actuation of a power switch 114, such as depicted in FIGS. 4A-2B, 4 and 9. The power switch 114 may be configured to toggle the motor 180 between on and off positions, where vibrations are produced when the motor 180 is on and vibrations are not produced when the motor 180 is off. As such, the power switch 114 may be a button, knob, lever, slide bar, electronic button or other suitable structure that can be actuated by a user to turn the motor 180 on or off. The power switch 114 may therefore be accessible from the exterior of the housing 110. The power switch 114 is used to complete the electrical circuit between the power source 130 and the motor 180 such that when the power switch 114 is in the "on" position, the circuit is completed or closed and the motor 180 is on, and when the power switch 114 is in the "off" position, the circuit is open and the motor 180 is deactivated. Accordingly, the circuit may include a first wire 182 connecting the power source 130 to the switch 114, a second wire 184 connecting the switch 114 to the motor 180, and a third wire 186 connecting the motor 180 to the power source 130, as depicted in FIG. 9. In certain embodiments, the power switch 114 may not be a binary switch but rather a potentiometer providing varying degrees of electrical connectivity between the power source 130 and motor 180, such that the operation of the motor 180 may be attenuated by the amount of power supplied to it as regulated by the switch 114.

To use the anesthetic lancing device 100, a user or operator inserts a disposable lancet 140 into the housing 110 with the head 144 and cap at the opening of the housing 110.

Once the lancet 140 is fully seated in the carriage 150 and retained by the retention members 154, the cap of the lancet 140 may be removed from the head 144, such as by twisting off. The user may then place the device 100 against the skin of the patient, such as the heel of an infant or a fingertip of a child or adult, such that the contact surface(s) 148 are contacting the target lancing site. In some embodiments, the user may press the power switch 114 once contact is made, activating the motor 180 and producing vibrations that are transmitted to the target lancing site through the contact surface 148. In other embodiments, the user may activate the motor 180 and begin vibrating the lancet 140 prior to contact with the patient's skin. In still other embodiments, such as at least one preferred embodiment, the user may first contact the target site with the contact surface 148 of the device 100 and then begin to slightly push the device 100 against the patient until lancet 140 achieves a first position within the housing 110, which is defined as when a first force is achieved and may be detected when the first indicator 174a is visible through the first indicator window 120a on the housing top 111, as shown in FIGS. 10A-10B. Once the first position is achieved and the first indicator 174a is visible, the user may press the power switch 114 to activate the motor 180 and vibration. Regardless of when the vibration commences or how much force is applied before vibration commences, the user maintains contact of the contact surface 148 against the skin of the patient at the target site while the lancet head 144 is vibrating for a predetermined minimal period of time, such as in the range of 0.1 seconds to 1 hour, preferably at least 5-30 seconds, and more preferably about at least 10 seconds. This provides enough time in which to produce a vibration-induced anesthetic effect at the patient's skin at the incision site.

While the contact surface 148 is vibrating, and preferably upon completion of the minimal vibration-inducing anesthetic period of time, the user may continue to slightly press the device 100 further into the skin of the patient, moving the lancet 140 further into the housing 110. In some embodiments, however, the lancet 140 may continue to be advanced into the housing 110 by pressing the device 100 into the skin during the time in which the vibration-induced anesthetic effect is being accomplished. When the lancet 140 reaches a second position within the housing 110, which may be defined by when a second force is detected and determined when the second indicator 174b is visible through an indicator window 120 in the housing top 111 such as a second indicator window 120b, as shown in FIGS. 11A-11B, the lancet 140 has reached a position primed for deploying the piercing member 146. When the lancet 140 has reached this second position, the piercing member 146 may be deployed by actuating the trigger 116. Notably, vibration at the target lancing site continues during deployment of the piercing member 146 to the target lancing site. Optimally, the contact surface 148 will have been in contact with and vibrating the skin of the target site for the full vibration-induced anesthetic time, preferably at least 10 seconds, prior to actuating the trigger 116 and deploying the piercing member 146. Due to the shallow penetration depth of the piercing member 146, both the vibrating skin moving relative to piercing member 146 and the rapidly inserting and vibrating piercing member 146 will achieve similar benefits of reduction of force for penetration, less pain and trauma from incision.

Once the piercing member 146 is deployed, it is propelled through the opening 115 of the lancet 140 and into the patient's skin at the target lancing site for blood collection. It is automatically returned to the lancet body 142 and retained therein according to the internal structure of the

lancet 140. The power switch 114 may again be actuated to turn the motor 180 off, halting the vibration. Standard protocol may then be followed for blood collection. The lancet may then be removed from the housing 110, such as by manually pulling the lancet 140 out through the opening in the housing 110. The retention members 154 of the carriage 150 are sufficiently resilient that they will flex and allow the lancet 140 to be removed upon manual force. The device 100 may also include a release button (not shown) that may be activated from the exterior of the housing 110 that will eject the lancet 140 from the carriage 150 and/or housing 110 when pressed.

EXAMPLES

The following examples demonstrate the feasibility of the anesthetic lancing device 100 of the present invention to reduce behavioral and neural responses to heel stick pain.

Example 1

Glucose and Metabolic Screening

Ten (10) neonatal patients (35-38 weeks' GA at birth) were enrolled into an IRB-approved crossover study. Each subject underwent two (2) heel sticks, one (1) with the anesthetic lancing device 100 of the present invention (with 15-second pre-lance vibration) (denoted as BGS in FIGS. 12A and 12B) and one with a standard of care lancet (Gentleheel®, Cardinal Health, Dublin, OH; non-vibrated) (denoted as Control in FIGS. 12A and 12B) in random order. Due to hospital discharge prior to the second lance, two (2) of the ten (10) subjects only underwent a single heel stick for a total of eighteen (18) heel sticks for analysis (n=3-5 scores treatment/screening type). Skin conductance (SC), a measure of sympathetic nervous system (SNS) activation, can be monitored by electrodermal responses (EDR) and is commonly reported as a rate of EDRs/sec. In this study, SC responses (#EDRs/sec) were assessed pre-lance ("Pre"), immediately following lance ("Pain"), and up to ten minutes post-lance ("Post").

The results shown in FIG. 12A indicate that SC activity was modulated by the heel lance stimulus in both treatment groups, though less so when using the anesthetic lancing device 100 of the present invention. Shifts in activity from Pre to Pain phase were greater with metabolic screening likely due to need to squeeze the heel following lance in order to obtain a greater volume of blood as compared to glucose screening, which requires a smaller collection volume. However, due to the small sample size, and small subgroup sizes (n=3-4), the results of the SC data were not statistically relevant, either in terms of #EDRs/second or mean EDR peak amplitudes. However, feasibility of SC measurements and lower sympathetic activity with the anesthetic lancing device 100 of the present invention versus a standard lancet was demonstrated on principle. Additional testing will be performed to confirm statistical relevance.

Facial actions were also video recorded for later behavioral scoring and analysis according to the Neonatal Facial Coding System (NFCS), a validated and widely accepted behavioral coding scale with high inter-rater reliability (0.84 to 1.0088) which assesses ten facial actions that are stereotypical of a neonate's reaction to noxious stimuli: brow bulge, eye squeeze, nasolabial furrow, open lips, horizontal mouth stretch, vertical mouth stretch, taut tongue, lip purse, chin quiver, and tongue protrusion. Two independent coders performed the NFCS assessment (inter-rater reliability of

>85%). To ensure coders were blinded to treatment condition, the video camera focused on infant face and upper body only and the audio was on mute. Analysis of mean NFCS scores demonstrated a non-significant but lowered NFCS score with both screening types (Glucose and Metabolic/other) when using the anesthetic lancing device 100 of the present invention with respect to lower heel stick behavioral responses, shown in FIG. 12B. This was particularly notable heel sticks for glucose screening ($p=0.15$). Glucose screens only require a small volume of blood, in the range of about 1-5 μ L, with minimal heel squeezing/manipulation needed, thus differentiation of behavioral responses may be more genuinely attributed to the lancing event. Individual baseline NFCS score was subtracted from score at peak during heel squeezing to calculate data in either representation.

Example 2

Cortical Pain Activity

A pilot neonatal IRB-approved clinical trial investigating cortical pain signal (measured via EEG) for heel sticks was conducted. Subjects (N=20, n=10/treatment) were enrolled and randomized to either the anesthetic lancing device 100 of the present invention (10 sec pre-lance vibration) (denoted as BGS in FIGS. 13A-14) or a control (same lancet; no vibration applied) (denoted as Control in FIGS. 13A-14). EEG data was gathered via electrodes placed onto the C3 and CP3 areas of the brain to collect electrical brain responses specific to heel lances. EEG signals recorded within 1000 ms following the heel lance were analyzed and are shown in FIG. 13A. The area under the curve was calculated using the integrated signal amplitude in the pre-specified 400-600 ms time window after the stimulus, which corresponded to the nociceptive specific activity. Topographic EEG data was also derived were derived using Cartool freeware and analyzed using aggregate data from each group to better inform the respective layout of the brain response to heel sticks with either device.

The results suggest a statistically significant reduction in EEG responses between the present anesthetic lancing device 100 and the control ($p=0.016$, effect size=1.188), as shown in FIG. 13B. The topographic map of the brain showed that with a standard lancet, almost the entire ipsilateral hemisphere of the brain and portions of the contralateral hemisphere were activated in response to the lance, as shown in FIG. 14. With the present anesthetic lancing device 100, however, a limited response concentrated more centrally was activated in response to the lance. EEG responses were detected in the short 1-second window following the lance, the magnitude of which was dependent on treatment, firmly demonstrating feasibility of the present anesthetic lancing device 100 to reduce the cortical pain signal. The topography data of FIG. 14 suggests that the present anesthetic lancing device 100 not only reduced the magnitude of signal but produced a different pattern of activity.

Additional Embodiments

The present invention is also directed to a lancing device 100' having an ejector 200, as shown throughout FIGS. 15A-21. In these embodiments, the lancing device 100' is as described above, which may or may not include the anesthetic feature discussed above, but further includes an integrated ejector 200 that provides a mechanism for removing the lancet from the lancing device 100' without the user having to manipulate the lancet or put their hands near the

needle of the lancet for removal. The ejector 200 of the present invention greatly increases the safety of the current lancing device 100' over currently available lancing devices. The ejector 200 can also be operated with the same hand that holds the lancing device 100', rather than two hands needed with other device—one to hold the device and another to remove the lancet—thus increasing the ease of use.

Specifically, FIGS. 15A and 15B show the lancing device 100' and ejector 200 thereof, in assembled and exploded views, respectively. The ejector 200 is mostly contained within the housing 110" of the lancing device 100' but includes an exterior portion 201 located outside of the housing 110". In such embodiments of the lancing device 100' having an ejector 200, the trigger 116 that deploys the piercing member 146 of the lancet 140 may be located on a different surface of the device 100' than the exterior portion 201 of the ejector 200 so that one does not interfere with the other. In at least one embodiment, as shown in FIG. 18A, the trigger 116 is located on a side surface of the device 100' and the exterior portion 201 of the ejector 200 is located on a top 111", though in other embodiments different locations for each are contemplated. Returning to FIGS. 15A and 15B, the exterior portion 201 may be a knob, button, or similar structure and may be made of plastic, metal or any suitable material. The exterior portion 201 may have any shape, size or configuration. In at least one example, as shown in FIGS. 15A-17C, the exterior portion 201 may be circular, though in other embodiments it may be oval, oblong, rectangular, square, triangular, pyramidal, or any other regular or irregular shape. The exterior portion 201 includes an actuator 202 which a user may interact with, such as by pushing or pressing, to maneuver the ejector 200 between the various positions, discussed in detail below, and expel a lancet 140 from the lancing device 100'. The actuator 202 may be a raised section of the exterior portion 201, such as shown here, and may extend along at least a portion of the exterior portion 201 to allow for increased user engagement. This length may be linear, curvilinear or of an ergonomic shape or configuration to facilitate user engagement for the application of force thereto. In some embodiments, the actuator 202 may optionally include tactile features such as bumps, ridges, grooves, frictional material and the like to increase traction and improve contact and interaction with the actuator 202.

The exterior portion 201 of the ejector 200 also includes an indicator 204 that is visible to a user. The indicator 204 may be a shape, icon, logo, color, light, or other visible component affixed to, integral with and/or extending from the surface of the exterior portion 201 of the ejector 200. The indicator 204 provides visual information to the user of the status and position of the ejector 200, such as whether the ejector is in a home or eject state, and thus whether the lancet 140 may be removed from the lancing device 100'. The housing 110", specifically the top 111" of the housing 110", includes indicia thereon which is also visible to the user. These indicia may include shape, icon, logo, color, light, or other visible component affixed to, integral with and/or extending from the surface of the housing 110". These indicia on the housing 110" provide reference for the status of the ejector 200 and therefore may correspond to the indicator 204 on the exterior portion 201 of the ejector 200. For instance, the indicia may include a home indicia 214 indicating a home position of the ejector 200 when the indicator 204 of the ejector 200 and the home indicia 214 of the housing 110" align. The indicia may also include an eject indicia 216 indicating an eject position of the ejector 200 when the indicator 204 of the ejector 200 and the eject

indicia 216 of the housing 110" align. The home indicia 214 and eject indicia 216 of the housing 110" are preferably different from one another and are located at different positions on the housing 110" relative to the ejector 200, to easily distinguish whether the ejector 200 is in a home or eject state. For instance, in at least one embodiment, the home indicia 214 and eject indicia 216 are spaced apart and preferably located 90 degrees from one another relative to a central axis 207 of the ejector 200 about which the ejector 200 rotates in moving between the home and eject states or positions.

The ejector 200 also includes an interior portion 205, shown in FIG. 15B. The interior portion 205 connects directly to the exterior portion 201, such as to the underside thereof, by adhesive, welding, or similar permanent affixation. The interior portion 205 includes at least a post 206 having an elongate length that joins and extends away from the exterior portion 201 along the central axis 207 into the internal space of the housing 110". The housing 110" also includes a slot 103 extending transversely to the central axis 207 of the ejector 200 and toward the first end 106 of the lancing device 100' and lancet 140 when loaded therein. At least a portion of the post 206 of the of the ejector 200 extends through and is movable within this slot 103. The slot 103 is therefore larger in size and dimension than the width of the post 206, but smaller in dimension than the exterior portion 201 of the ejector 200 so the exterior portion 201 remains on the outside of the housing 110" and the post 206 may move within the length of the slot 103, such as by slidable movement when the actuator 202 of the exterior portion 201 is moved such as by pushing. The slot 103 determines the limits of rotational and linear movement of the ejector 200 during use. The post 206 may only move within the confines of the slot 103, both rotationally and linearly. Thus, the length of the slot 103 limits how far and in what direction the ejector 200 may be moved relative to the housing 110". The width of the slot 103 is wider than the diameter of the post 206 so that the post 206 may rotate freely within the slot 103 when the actuator 202 is engaged.

The top 111" of the housing 110" may include a track 104, as seen in FIGS. 15A and 15B, in which the exterior portion 201 of the ejector 200 may be moved as the post 206 of the interior portion 205 moves through the slot 103. Accordingly, the track 104 coincides with and is preferably coaxial with the slot 103. In some embodiments, the track 104 may be a recess or indentation in the top 111" of the housing 110" as shown in FIGS. 15A and 15B, physically limiting and directing the linear movement of the exterior portion 201 of the ejector 200. Accordingly, the track 104 may have dimensions larger than those of the exterior portion 201 of the ejector 200, such as the width thereof. The track 104 may also receive and permit movement of the exterior portion 201 of the ejector 200 therein when the actuator 202 is pushed or pressed. In other embodiments, the track 104 may be markings on the top 111" of the housing 110" that visually delineate the movement path of the exterior portion 201 of the ejector 200 but are otherwise flush with the surface of the top 111".

The interior portion 205 of the ejector 200 also includes an arm 208 extending from the post 206 transverse to the length of the post 206 and the central axis 207, as best shown in FIGS. 15B and 16A-16C. In at least one embodiment, the arm 208 extends from a terminal end of the post 206, though it may extend from any position along the length of the post 206 spaced apart from the exterior portion 201. The arm 208 has an elongate length and a terminal end 209 which will contact the rear 143 of the lancet 140 when selectively

moved into position to push the lancet 140 out of the device 100', as described in greater detail below. The length of the arm 208 may be any length that the housing 110" may accommodate. For instance, the arm 208 may have the same, lesser or greater length as a dimension of the exterior portion 201. In some embodiments in which the exterior portion 201 is circular, the length of the arm 208 may be less than, equal to or greater than the radius of the exterior portion 201. For instance, when less than the dimension of the exterior portion 201, the length of the arm 208 does not extend beyond the perimeter of the exterior portion 201. When equal, the terminal end 209 of the arm is co-terminal with the perimeter of the exterior portion 201. When greater than the exterior portion 201, the terminal end 209 of the arm 208 extends beyond the perimeter of the exterior portion 201, such as shown in FIGS. 16A-16C.

In some embodiments, the interior portion 205 of the ejector 200 may also include a guide 210, as seen in FIGS. 15B and 16A. The guide 210 also extends radially from the post 206 and is spaced apart from the arm 208. The guide 210 may extend from the same radial angle from the post 206 as does the arm 208, or it may extend from a different radial angle. Accordingly, in at least one embodiment, as shown in FIGS. 15B and 16A, the guide 210 may extend from the post 206 at a 180° angle relative to the arm 208, though in other embodiments it may extend at any angle between 0° and 360° relative to the arm 208. The guide 210 may also extend from the post 206 at the same radial angle as the actuator 202 extends along the exterior portion 201, or at a different radial angle as the actuator 202 along the exterior portion 201. For instance, as shown in FIGS. 16A and 16C, the guide 210 may extend radially from the post 206 at a 90° angle relative to the actuator 202, though in other embodiments it may extend at any angle between 0° and 360° relative to the actuator 202. The guide 210 is sized to fit between walls 102 that flank the slot 103, as described in greater detail below with respect to FIGS. 19C and 20C, and therefore keeps the ejector 200 properly aligned and from rotating during movement of the ejector 200 and expulsion of the lancet 140. In other embodiments however, such as shown in FIGS. 22B, 22C, 23B, 23C, 24B, 24C, 25B and 25C, the ejector 200' may include a post 206 and arm 208 radially extending therefrom, but no guide. In such embodiments, the post 206 extending through the slot 103 keeps the ejector 200' properly aligned relative to the lancet 140'.

In some embodiments, the interior portion 205 of the ejector 200 may also include at least one collar 211, as shown in FIG. 16A. The collar 211 is located along the post 206. In at least one embodiment, the collar 211 is located between the exterior portion 201 and the arm 208. The collar 211 at least partially encircles the post 206 and extends radially therefrom by a distance, though in at least one embodiment the collar 211 radially extends a distance less than that of the arm 208 or guide 210. The collar 211 is positioned along the post 206 and configured to engage a biasing member 218, such as by contacting, receiving and/or retaining a portion of a biasing member 218 as depicted in FIG. 21, to maintain the biasing member 218 in its contact position along the post 206, as described in greater detail below. In at least one embodiment, the ejector 200 includes a first collar 211a and a second collar 211b spaced apart from each other along the post 206. The collars 211a, 211b may have the same or different dimensions as one another. For instance, in the embodiment shown in FIG. 16A, the second collar 211b may have a longer dimension along the post 206 compared to the first collar 211a, though the first and second

collars 211a, 211b may each extend radially from said post 206 by the same distance. This is but one non-limiting example. The first collar 211a may be positioned intermediate between the exterior portion 201 and the arm 208, whereas the second collar 211b may be positioned partially intermediate between the exterior portion 201 and the arm 208 and partially coextensive with the arm 208, as shown in FIG. 16A. In other embodiments, however, both first and second collars 211a, 211b may be located intermediate between the exterior portion 201 and the arm 208. In some embodiments, the collars 211a, 211b may be adjustable in position along the length of the post 206 as desired, though in at least one embodiment they are fixed in position. The first and second collars 211a, 211b are spaced apart from one another along the post 206 by a distance sufficient to accommodate the biasing member 218 therebetween, such that the first and second collars 211a, 211b collectively retain the biasing member 218 in its contact position along the post 206 and prevents the biasing member 218 from migrating up or down the post 206 beyond the collars 211a, 211b. This helps keep the biasing member 218 in place, which is particularly helpful as the ejector 200 is rotated between the home and first eject positions, described in greater detail below.

The carriage 150' receives and retains the lancet 140, 140' therein as described above. As with the previous embodiments, the carriage 150' includes retention members 154 which frictionally hold a lancet 140, 140' when inserted in the carriage 150' and connection points 164, as shown in FIGS. 16A and 16B, where isolation members 162 may attach and suspend the carriage 150' within the housing 110". In these embodiments having an ejector 200, 200', the carriage 150' is defined by a top 152, a bottom 153 and a space extending therebetween. As shown in FIGS. 15B-17C, the top 152 and bottom 153 of the carriage 150' are parallel and spaced apart from one another. The space between them extends from the open distal end 151a of the carriage 150' and the proximal end 151b at the opposite end of the carriage 150', as seen in FIGS. 16A-17C. The distal end 151a of the carriage 150' may also be referred to as the front of the carriage 150' and is the end which receives the lancet 140 and through which the lancet 140 is ejected. Accordingly, the distal end 151a of the carriage 150' is positioned at the first end 106 of the lancing device 100'. The proximal end 151b of the carriage 150' may also be referred to as the rear or back of the carriage 150' and is positioned within the interior space of the housing 110".

The opening at the distal end 151a of the carriage 150' is sufficiently sized to receive a lancet 140, 140', such as the entire width or substantially the entire width of the distal end 151a of the carriage 150'. The vertical dimension of the space, extending between the top 152 and bottom 153 of the carriage 150', is substantially the same size as the height of the lancet 140, 140'. This provides a tight fit for frictional engagement of the lancet 140, 140' within the carriage 150' during use and secured by the retention members 154. The proximal end 151b of the carriage 150' may have the same or different dimensions as the open distal end 151a. In at least one embodiment, as best shown in FIG. 16C as compared to FIG. 16B, the proximal end 151b may be the same width as the distal end 151a but includes an opening that is smaller than the opening at the distal end 151a. The opening at the proximal end 151b need not extend the full width of the carriage 150' but is at least as wide as the arm 208 of the ejector 200. Accordingly, the proximal end 151b may also act as a backstop for the lancet 140, 140' when fully inserted in the carriage 150'. In at least one embodiment, the

opening at the proximal end 151b extends from one lateral side of the carriage 150' to substantially the center of the carriage 150', as shown in FIG. 16C. The opening at the proximal end 151b of the carriage 150' is therefore sufficiently sized and dimensioned to receive the arm 208 of the ejector 200 there through.

Since the carriage 150' holds the lancet 140, 140' during use, the ejector 200, 200' must also interact with the carriage 150' to expel the lancet 140 when it is time to discharge the lancet 140. Accordingly, the ejector 200 and carriage 150' are shown in relation to each other in exploded views in FIGS. 16A-16C, and in assembled views in FIGS. 17A-17C. The lancet 140 and remainder of the anesthetic lancing device 100' are omitted from these views for clarity.

As seen in FIGS. 16A-16C, the ejector 200 is aligned with the carriage 150' and specifically with the proximal end 151b of the carriage 150'. The ejector 200 is selectively movable toward and away from the carriage 150' when the actuator 202 is engaged. For instance, when the device 100' is assembled, the ejector 200 and carriage 150' are proximate to one another, as shown in FIG. 17A. In this figure and embodiment, the ejector 200 is shown in a home position in which the arm 208 is parallel to and spaced apart from the opening at the proximal end 151b of the carriage 150'. When the actuator 202 of the ejector 200 is manipulated, turning or rotating the ejector 200 from the home position to a first eject position, as shown in FIG. 17B, the arm 208 of the ejector 200 is rotated 90° from its home position. In this first eject position, the arm 208 of the ejector 200 is now perpendicular to and extending into the opening at the proximal end 151b of the carriage 150'. Finally, when the actuator 202 is further manipulated to push the ejector 200 forward in the slot 103 and track 104 (not shown here), to achieve the second eject position shown in FIG. 17C, the arm 208 of the ejector 200 is advanced through the opening in the carriage 150' from the proximal end 151b toward the distal end 151a until further progression is prevented by the post 206 contacting the carriage 150', such as the top 152 of the carriage 150'. Each of these positions will now be explained in greater detail.

FIGS. 18A-18C show a first embodiment of the lancing device 100' with ejector 200 in a home position. In this position, the ejector 200 is fully retracted and as proximally located within the housing 110" as possible. The exterior portion 201 is seated as proximally within the track 104 on the top 111" of the housing. The indicator 204 of the ejector 200 is aligned with the home indicia 214 located on the top 111" of the housing 110", which may be any shape, color or icon, but in the embodiment shown here is an icon of a home to indicate the baseline position for the ejector 200 when the lancing device 100' is in use as described above. Thus, a user can quickly and easily tell what position the ejector 200 is in by simply looking at the top 111" of the housing and seeing which indicia the indicator 204 is aligned with.

Inside this embodiment of the anesthetic lancing device 100', shown in the cutaway view of FIG. 18B, the arm 208 of the ejector 200 is positioned parallel to and spaced apart from the opening of at the proximal end 151b of the carriage 150' when in the home position, as described earlier. In this home position, the arm 208 is not engaging the carriage 150' or lancet at all. The anesthetic lancing device 100' is loaded with a lancet 140 and operated while the ejector 200 is in the home position so the ejector 200 does not interfere with the lancet 140 or the vibrations being imparted by the device 100'.

The underside interior of this embodiment of the device 100', shown in FIG. 18C, shows the guide 210 is positioned

perpendicular to the slot 103 in the home position. When so positioned, the guide 210 is longer than the width of the slot 103. The underside of the top 111" also may include walls 102 at the perimeter of the slot 103 and extending at least part of the length of the slot 103. In a preferred embodiment, as shown in FIG. 18C, a first wall 102a has a shorter length than an opposite second wall 102b. The guide 210 is positioned against the second wall 102b and the arm 208 abuts the first wall 102a transversely. Hence, the first wall 102a prevents the arm 208, and the ejector 200, from moving forward in the slot 103. Effectively, the walls 102 and the guide 210 collectively maintain the ejector 200 in the home position.

When use of the lancet 140 is completed and it is desired to remove the lancet 140, the user engages the actuator 202 of the ejector 200 to initiate the ejection process. The first step is to move the ejector 200 from a home position to a first eject position, as shown in FIGS. 19A-19C. In this first eject position, the actuator 202 is engaged to rotate the exterior portion 201 of the ejector 200, such as by 90°. The actuator 202 is engaged by the user applying rotational, torque or torsional force or pressure to the actuator 202, which terms may be used interchangeably herein. This pressure on the actuator 202 rotates the exterior portion 201 of the ejector 200 so that the indicator 204 on the exterior portion 201 now aligns with or is in proximity to the eject indicia 216 on the top 111" of the housing 110", as shown in FIG. 19A. The eject indicia 216 may be any shape, color or icon, but in the embodiment shown here is a forward arrow, indicating the position from which movement of the ejector 200 is possible. However, in this first eject position, the only movement that has occurred is the rotational movement needed to unlock the ejector 200. The ejector 200 is still fully proximal in the track 104. Hence, this position may also be referred to as a retracted eject position. Additionally, though clockwise rotation is depicted in the Figures, it should be appreciated that counterclockwise rotation is also possible and contemplated herein, depending on the interior portion 205 of the ejector 200, 200', the slot 103 and the direction of torsional force applied to the actuator 202. It should also be appreciated that any degree of rotation may be defined as the full amount of rotation. Here, 90° is illustrated as full rotation, though in other embodiments it may be 180°, 270°, 360° or anywhere therebetween.

Rotation of the exterior portion 201 of the ejector 200 outside the housing 110" results in a similar rotation of the arm 208 inside the housing 110", as shown in FIG. 19B. As it does so, the arm 208 breaks the plane of and moves through the opening at the proximal end 151b of the carriage 150', as also shown in FIG. 17B. In the first eject position of FIG. 19B, the arm 208 is now perpendicular to and extends through the opening at the proximal end 151b of the carriage 150'. However, the arm 208 is still spaced apart from the lancet 140 and does not touch it yet in this embodiment.

Viewing the ejector 200 and carriage 150' from underneath, as in FIG. 19C, the guide 210 is now parallel to the slot 103 in the first eject position. The guide 210 fits within walls 102 defining the outer lateral perimeter of the slot 103. As can be seen in FIG. 19C, a first wall 102a may be shorter in length than a second wall 102b opposite the first. This difference in length creates a space through which the guide 210 may move as the ejector 200 is rotated when moving from a locked position to a first eject position. Now that the guide 210 is positioned between and parallel to the walls 102 on either side of the slot 103, it is able to keep the arm 208 aligned as the ejector 200 is moved in later steps.

In at least one embodiment, once the ejector 200 is in the first eject position, it may be moved forward or distally in the direction of the lancet 140 to eject the lancet 140, as shown in FIGS. 20A-20C. To accomplish this, the actuator 202 of the ejector 200 is engaged, such as by pushing with a thumb or finger away from the user and in the direction of the first end 106 of the 100'. As this is performed, the exterior portion 201 of the ejector 200 is moved in the distal direction along the track 104 of the top 111" of the housing 110", as shown in FIG. 20A. As this occurs, the arm 208 within the housing 110" is moved toward the lancet 140 until it contacts the rear 143 of the lancet 140, specifically at the terminal end 209 of the arm 208, defining an intermediate position shown in FIG. 21. As pressure is continued to be applied to the actuator 201, the arm 208 puts increasing pressure on the rear 143 of the lancet 140 until the force on the lancet 140 is sufficient to overcome the frictional forces holding the lancet 140 in the carriage 150' and the lancet 140 is expelled from the carriage 150'. The arm 208 continues to push on the lancet 140 from the rear 143 until the lancet 140 has moved through the opening 115 in the housing 110" at the first end 106 of the device 100' and the lancet 140 is expelled from the device 100'. The ejector 200 continues to move in the distal direction when pushed until the post 206 reaches the end of the slot 103. When this occurs, the ejector 200 has reached a second eject position in which the ejector 200 is as far forward or distal in the housing 110" as is possible, as shown in FIG. 20B. This coincides with the distal-most position of the exterior portion 201 in the track 104 shown in FIG. 20A. In some embodiments (not shown) the post 206 may also contact a portion of the carriage 150' when it reaches the end of the slot 103.

Similarly, when viewed from underneath, as depicted in FIG. 20C, the guide 210 may help keep the arm 208 aligned with the slot 103 and angled toward the lancet 140 as the ejector 200 moves distally toward the lancet 140 and then continues to push the lancet 140 through the opening 115. In addition to the above, the second eject position may also be defined when the post 206 has reached the distal end of the slot 103. In some embodiments, a bearing surface of the post 206 may contact the terminal end of the slot 103 to prevent further forward movement of the ejector 200. In the second eject position, the lancet 140 is fully ejected from the housing 110" and the ejector 200 is as far in the distal direction as it is possible to go.

As shown in FIG. 21, the lancing device 100' also includes a biasing member 218 that contacts a portion of the ejector 200 and provides a biasing force against the ejector 200 to urge it back in the proximal direction toward the interior of the housing 110". Accordingly, the presence of the biasing member 218 against the post 206 or other part of the ejector 200, 200' may keep the ejector 200, 200' from proximal movement until force is intentionally applied to the actuator 202, as described above, and the biasing force imposed by the biasing member 218 on the ejector 200, 200' at rest is overcome. In at least one embodiment, the biasing member 218 may contact the post 206 of the ejector 200, such as a portion of the bearing surface of the post 206 as shown in FIG. 21 and biases the post 206 against the interior of the housing 110". The biasing member 218 may be an elastomeric material such as rubber, plastic or other similarly resilient material anchored to the interior of the housing 110". In at least one embodiment, the biasing member 218 may be stretched at least partially around the post 206, as shown in FIG. 21. As the ejector 200 moves distally toward the first end 106 of the device 100', the biasing member 218 becomes increasingly stretched and taut. Once the pressure

on the actuator 202 is relieved, such as when the lancet 140 is fully ejected, the ejector 200 has achieved the second eject position and pressure on the actuator 202 is released, the biasing force stored up within the biasing member 218 as a result of such stretching may be discharged, pushing the post 206 and therefore ejector 200 back into the housing 110" and the first eject position. At this point, the actuator 201 may be engaged to rotate the exterior portion 202, and consequently the entire ejector 200, back into the home position. Though described here as an elastomeric band, in other embodiments the biasing member 218 may be a spring that is anchored to the housing 110" near the opening 115 at the distal end, for instance, and is compressed as the ejector 200 contacts it and/or is moved distally and then expands to push the ejector 200 back toward the interior of the housing 110" once pressure on the ejector 200 is released.

The lancing device 100' with ejector 200 can accommodate different lancets 140' with different configurations and dimensions, such as but not limited to that shown in FIGS. 22A-25C. These lancets 140' may sit further back or more proximally in the carriage 150' and/or housing 110" or may have a longer depth such that the rear of the lancet 140' is positioned more proximally within the housing 110" when fully seated in the carriage 150' than those discussed previously. Indeed, the rotation of the ejector 200, 200' allows for the use of various different lancets 140', permitting the arm 208 to be sufficiently long to reach and eject even the shallowest of lancets 140' while also allowing the housing 110" to be more compact than other lancing devices. In some embodiments, the carriage 150' receiving and retaining such lancets 140' may itself have the same dimensions and configuration as described and shown above, and as illustrated in FIGS. 22A-25C. In other embodiments, however, a carriage 150' with different dimensions or configurations may be used in the lancing device 100' to accommodate different lancets 140' and may even be customized for particular lancets 140'.

Because of the more proximal placement of the rear of the lancet 140' within the housing 110" in some embodiments, the arm 208 of the ejector 200, 200' may contact the rear of the lancet 140' during rotation from the home position to the first eject position. Thus, the intermediate position is achieved before full rotation of the ejector 200, 200'. This is illustrated in FIGS. 22A-25C. Further rotation remains possible once contact is made, as will now be described.

For instance, in a second embodiment of the lancing device 100', the ejector 200' begins in the home position shown in the top plan view, top cutaway view and bottom cutaway view of FIGS. 22A-22C, respectively. The arm 208 of the ejector 200' is perpendicular to and spaced apart from the rear of the lancet 140' in the home position.

As torque is applied to the actuator 202 and the ejector 200' begins to rotate, but before reaching full rotation, the arm 208 contacts the rear of the lancet 140', as shown in FIGS. 23A-23C. When viewing the lancing device 100' from the outside, as in FIG. 23A, the indicator 204 is not aligned with either the home indicia 214 or the eject indicia 216 but is instead located somewhere between them when contact is achieved and the intermediate position is obtained. Preferably, the user may also feel the point at which contact is made, such as by encountering resistance to the force being applied to the actuator 202, verifying contact has been made. The intermediate position and contact of the arm 208 with the rear of the lancet 140' is shown from above in FIG. 23B and below in FIG. 23C. Contact of the arm 208 with the rear of the lancet 140' may occur anywhere along the continuum within the full rotation of the ejector 200', such as but not

limited to anywhere greater than 0° rotation and less than 90° rotation. In at least one embodiment, contact may occur at 45° rotation, as shown in FIGS. 23B and 23C. In embodiments in which full rotation may be defined differently, such as up to 180°, 270° or 360° rotation, the intermediate position and contact between the arm 208 and rear of the lancet 140' may occur at any point between the home position (as 0°) and the full extent of possible rotation. The precise angle of rotation needed for contact between the arm 208 and the rear of the lancet 140' depends in the length of the arm 208 and the depth at which the rear of the lancet 140' sits within the housing 110".

Because contact between the arm 208 and the rear of the lancet 140' occurs before full rotation is complete in this embodiment, additional torque applied to the actuator 202 and further rotation of the ejector 200' is possible even after contact is made. As a user continues to apply torque or rotational force to the actuator 202, rotation of the ejector 200' continues until the first eject position is reached, as shown in FIGS. 24A-24C. In this first eject position, the indicator 204 aligns with the eject indicia 216, as shown in FIG. 24A. Looking to the interior of the device 100' in FIGS. 24B and 24C, as additional force is applied to complete the rotation of the ejector 200' from the intermediate position to the first eject position, the arm 208 pushes on the rear of the lancet 140' as it rotates. This moves the lancet 140' distally within the carriage 150'. When the first eject position is reached, the arm 208 remains in contact with, and applying pressure to, the rear of the lancet 140' and the lancet 140' is no longer fully seated in the carriage 150', but it is still retained within the carriage 150' and not fully ejected.

Upon linear force being applied to the actuator 202, the ejector 200' is driven translationally along the slot 103 in the distal direction toward the first end 106 of the housing 110", as demonstrated in FIGS. 25A-25C. As the ejector 200' moves linearly in the slot 103, the arm 208 continues to apply force to the rear of the lancet 140' through the contact point, pushing the lancet 140' further distally in the carriage 150' for ejection. By the time the ejector 200' reaches the end of the slot 103, and thus the second eject position shown in FIGS. 25A-25C, the lancet 140' is fully ejected from the lancing device 100' through the opening 115.

In some embodiments, such as those lacking wall(s) 102 associated with the slot 103 and/or ejectors 200' lacking a guide 210, there may be nothing to prevent distal translational movement of the ejector 200, 200' from any position upon the application of force to the actuator 202, be it from the home position, intermediate position, or first eject position, even without rotation. In such embodiments, rotational movement of the ejector 200, 200' prior to the arm 208 contacting the lancet 140, 140' still may be preferable, since sufficient vector forces applied to the lancet 140, 140' are needed for translational motion and ejection. For instance, the ejector 200, 200' may need to be rotated by a minimum amount of angular rotation prior to contact between the arm 208 and lancet 140, 140' to achieve such vector forces. One example is at least 45° angular rotation prior to contact, though lesser and greater degrees of minimal rotation are also contemplated.

It should be appreciated from the above description that the ejector 200, 200' can be operated with a single hand and/or digit by the user. Indeed, it should be possible for the user to hold and operate the lancing device 100' with a single hand, activating the vibrations and deploying the lancet by pressing respective actuator buttons for each, and then with the same hand also rotate the ejector 200, 200' and push it forward to eject the lancet 140, 140' once use of the lancet

140, 140' is completed. In this manner, the user of the device 100' does not have to touch or reach near the piercing member 146 of the lancet 140, 140' to remove it. This increases the safety of the device 100'. The single-handed operation also increases the efficiency and ease of use of the device 100'.

Since many modifications, variations and changes in detail can be made to the described preferred embodiments, it is intended that all matters in the foregoing description and shown in the accompanying drawings be interpreted as illustrative and not in a limiting sense. Thus, the scope of the invention should be determined by the appended claims and their legal equivalents. Now that the invention has been described,

What is claimed is:

1. A lancing device for piercing the skin of a patient, comprising:
  - a housing including an opening dimensioned to receive a lancet therein, and a slot disposed along a portion of said housing; and
  - an ejector having an exterior portion located outside said housing, a post extending from said exterior portion through said slot, an arm extending radially from said post within said housing, said ejector selectively adjustable rotationally and intermediately between:
    - (i) a home position wherein said arm is spaced apart from said lancet; and
    - (ii) a first eject position wherein said arm is aligned with said length of said slot; and
  - said ejector selectively adjustable longitudinally and intermediately between:
  - (iii) said first eject position; and
  - (iv) a second eject position wherein said lancet is ejected from said housing by said arm; and
  - further comprising one of:
  - (v) said ejector is further selectively adjustable to and from an intermediate position wherein said arm of said ejector contacts said lancet, said intermediate position of said ejector being between said home position and said first eject position, and further being at least 45.deg. from said home position; said ejector being between said home position and said first eject position, and further being at least 45.deg. from said home position;
  - (vi) a carriage retained within said housing, said carriage configured to receive and retain said lancet when inserted in said housing, said carriage comprising an open distal end, an opposite open proximal end, and a space extending between said distal and proximal ends, said space dimensioned to receive a body of said lancet therein, and wherein said arm of said ejector is: (a) parallel to and spaced apart from said open proximal end of said carriage in said home position, (b) perpendicular to and at least partially entering said open proximal end in said first eject position, and (c) within said space of said carriage in said second eject position; and
  - (vii) a guide extending radially from said post within said housing by one of (a) the same radial angle from said post as said arm and (b) a different radial angle from said post as said arm. said guide further comprising a first wall along a portion of a longitudinal side of said slot within said housing, said guide being perpendicular to said first wall in said home position and parallel to

said first wall in said first and second eject positions. wherein contact between said first wall and said guide in said home position prevents longitudinal movement of said ejector along said slot.

5. 2. The lancing device as recited in claim 1, wherein said ejector is selectively adjustable rotationally by up to 90° between said home position and said first eject position.
3. The lancing device as recited in claim 1, wherein said ejector is selectively adjustable longitudinally along said slot once said ejector is no longer in said home position.
4. The lancing device as recited in claim 3, wherein said ejector is selectively adjustable longitudinally along said slot from said intermediate position.
15. 5. The lancing device as recited in claim 1, wherein said housing has a first end including said opening and an opposite second end, wherein said slot includes a length defined between a distal end nearest said first end of said housing and a proximal end nearest said second end of said housing, and said ejector is located at said proximal end of said slot in said home position and said first eject position, and at said distal end of said slot in said second eject position.
20. 6. The lancing device as recited in claim 1, wherein said carriage retains said lancet by frictional forces, said arm of said ejector transferring force applied to said exterior portion of said ejector to said lancet when in contact with said lancet, and said arm expels said lancet from said carriage when said force applied to said exterior portion of said ejector exceeds said frictional forces retaining said lancet in said carriage.
25. 7. The lancing device as recited in claim 1, further comprising an indicator on said exterior portion of said ejector and at least one indicia on said housing visible from outside said housing, wherein the relationship between said indicator and said indicia is indicative of the position of said ejector.
30. 8. The lancing device as recited in claim 7, wherein said at least one indicia further comprises a home indicia and an eject indicia, wherein said ejector is in said home position when said indicator aligns with said home indicia and said ejector is in said first eject position when said indicator aligns with said eject indicia.
35. 9. The lancing device as recited in claim 1, wherein said guide is spaced apart from said arm along said post.
40. 10. The lancing device as recited in claim 1, further comprising a biasing member mounted within said housing and biasing said ejector against said housing, said biasing member urging said ejector toward said first eject position when pressure is relieved from said exterior portion of said ejector.
45. 11. The lancing device as recited in claim 1, further comprising a motor selectively actuated to generate vibrations; said lancet having a head and a piercing member extending from said head; a contact surface disposed proximate to said piercing member on an exterior surface of one of said housing and said head of said lancet, said contact surface in mechanical communication with said motor and a target site on said patient, said contact surface translating said vibrations from said motor to said target site.
50. 12. The lancing device as recited in claim 11, wherein said motor is operative to vibrate said contact surface at a frequency in the range of 50-500 Hz.
